UNITED STATES PATENT OFFICE

WALTER A. GOERTZ, OF EAST ORANGE, NEW JERSEY, ASSIGNOR TO AUGUST GOERTZ & COMPANY, INC., A CORPORATION OF NEW JERSEY

DESIGN FOR A VANITY BOX

Application filed August 27, 1930. Serial No. 36,790. Term of patent 7 years.

To all whom it may concern:

Be it known that I, WALTER A. GOERTZ, a citizen of the United States, residing at East Orange, in the county of Essex and State of New Jersey, have invented a new, original, and ornamental Design for Vanity Boxes, of which the following is a specification, reference being had to the accompanying drawings, forming part thereof.

In said drawings, Figure 1 is a front face view, Figure 2 is a top end view, and Figure 3 is a side edge view of a vanity box, showing my new design.

I claim:—

The ornamental design for a vanity box, as shown.

WALTER A. GOERTZ.
